UNITED STATES PATENT OFFICE

JACOB C. MILLER, OF MILWAUKEE, WISCONSIN, ASSIGNOR, BY MESNE ASSIGNMENTS,
TO THE FULLER COMPANY, A CORPORATION OF WISCONSIN

DISPENSING-NOZZLE DEVICE

Application filed September 12, 1927. Serial No. 218,948.

This invention relates to improvements in dispensing nozzle devices. The invention has particular reference to nozzles for use in connection with tank vehicles which dispense 5 gasoline, fuel oil and the like to the reservoirs or buried tanks of customers. The invention is likewise adapted for use in other fields.

The primary object of the invention is to provide a nozzle with an automatically operable valve which will close in time to prevent overflow of the receptacle to which liquid is being dispensed. Referring specifically to the above indicated use of the nozzle on tank wagons, it may be pointed out that the 10 customer's receptacle is usually provided with a single pipe through which the fuel must be supplied and there is no means whereby the operator may be kept advised of the exact depth of liquid in the subterranean tank. 15 Moreover, the filler pipe is usually located in a grass plot which is wholly or partially destroyed in the event of over flow. In order to guard not only against loss of the fuel but also against damage to surrounding property 20 it is the purpose of the invention to provide a nozzle designed to fit within an ordinary filler pipe and operable entirely automatically whereby to dispense with any requirement for care on the part of the operator.

Further objects of the invention relate to the provision of means for tripping the valve with substantial immunity against accidental operation thereof; means for holding the valve open with great rigidity but readily responsive to the light pressure of a float; means for guarding the float from direct action or impact of the incoming stream of liquid; and means for setting the valve in an open position and visually indicating the trip 35 action.

In the drawings:

Figure 1 is side elevation of a device embodying this invention as it appears inserted in a tank which is shown in section.

Figure 2 is an axial section on an enlarged scale through the device shown in Figure 1.

Like parts are identified by the same reference characters throughout the several views.

The extreme top of the receiving receptacle

is shown fragmentarily at 5 and the filler pipe 6 extends therefrom to the surface of the ground 7.

A filling or dispensing nozzle 10 embodying this invention is connected to the tank vehicle in the usual manner by a hose or the like 11. The tubular portion 12 is of such dimensions as to fit within pipe 6 and extend therethrough into the receiving receptacle 5.

The tube 12 is closed adjacent its lower end by a partition 13 which provides a guide for valve stem 14 and protects float 15 from direct impact of the stream of liquid dispensed. Immediately above partition 13 are the ports 16 controlled by the valve sleeve 17 to which stem 14 is connected by means of a transverse web 18. Figure 2 shows the valve in its open position wherein it is supported above openings 16. It will be obvious that if released the valve will fall upon partition 13 to close ports 16.

Below the partition, the stem 14 is reduced in diameter by an annular groove 20 of hour glass contour as clearly indicated in Figure 2. When the valve and stem are in open position the groove 20 is engaged by the shorter ends of the two pawl levers 21 which are pivoted beneath partitions 13 upon either side of the valve stem. The portions of the pawls which engage in groove 20 are preferably approximately in a common diametrical plane through the stem and the ports are so proportioned that although the curvature of the groove 20 in profile is almost concentric with the fulcrums of the respective levers 21, the lever arms are too long to reach a horizontal position. The greater the downward pressure of the valve, the greater will be the wedging action of the pawls but the deviation of the profile of groove 20 from true concentricity is such that the pawls can oscillate freely and without binding toward a releasing position indicated in dotted lines.

For the release of the pawls 21 each of them is provided with an elongated arm 22 offset in opposite lateral directions to clear the valve stem at either side thereof. These arms project to opposite sides of the device from their respective fulcrums, thus develop-

ing a considerable leverage for the release of the valve. At their respective ends they carry rounded heads 23 adapted to be contacted by the float 15. The float normally rests on a cross pin 25 at the lower end of the nozzle and may be guided both by the enclosing tube and by the valve stem 14 which passes partially therethrough. The nozzle is slotted at 26 to give free access of the liquid in receptacle 5 to the chamber in which the float operates. If the float is made of some non-metallic material such as cork, it may be desirable to provide a metallic disk 27 thereon to reduce friction between the float and the bearing portions 23 of the lever pawls.

The device is set by lifting the valve to the open position in which it is shown in full lines in Figure 2. The weight of arms 22 of pawls 21 is such that the pawls will automatically grip the groove 20 when the groove registers therewith. The initial setting may either be accomplished manually preliminarily to introducing the nozzle into the filler pipe or else mechanical setting means may be provided, such as the wire 28 which is connected with the valve and passed upwardly through the nozzle to issue therefrom through boss 29. The location of the handle portion 30 of wire 28 above the boss 29 will obviously indicate to the operator the position of the valve.

When tank 5 is nearly full, the float 15 will be buoyed up and will contact the bearing portions 23 of the arms 22 of lever pawls 21, thereby oscillating said pawls simultaneously to a position shown in dotted lines in which the valve stem will be released. The design is such that binding is impossible in the releasing movement of the ports.

When the pawls are adjusted to releasing position the valve stem and valve will fall to close, or approximately close the ports 16 and simultaneously to give visible indication of the closing movement by means of wire 28 and handle 30.

It is extremely important to note that the float does not directly actuate either the valve or the indicating means. It would be impractical to provide within the dimensions of filler pipe 6 a float having sufficient buoyancy even to lift the indicator wire or rod 28, not to mention the valve. Consequently the arrangement is such that gravity furnishes the power and the float merely controls the movement.

Since it may be assumed that an operator will always be in charge of the apparatus, it is broadly immaterial whether the valve or the indicator is relied upon. Either device alone will prevent overflow. For the same reason, it is not necessary that the valve 17 should entirely cut off flow. The float controlled trip will operate before receptacle 5 is entirely full and the attention of the oper-

ator will be caught by the diminution of flow in time to shut off the supply tank valve at the vehicle. Diminution of flow will be apparent both audibly and by reference to the flow meter of the vehicle.

The particular structures disclosed have been selected as merely illustrative of the possibilities and it will be obvious that many alternative means may be employed within the scope of the appended claims.

I claim:

1. The combination with a tube provided with an outlet port and a valve therefor, of a stem for said valve shouldered in curvilinear profile, a pawl lever provided with a fulcrum and having one arm engageable with said shoulder and movable from engagement therewith in a path deviating therefrom in a direction opposite to valve closing movement of said stem, together with means for oscillating said lever.

2. The combination with a tube provided with an outlet port and a valve therefor, of a stem for said valve shouldered in curvilinear profile, a pawl lever provided with a fulcrum and having one arm engageable with said shoulder and movable from engagement therewith in a path deviating therefrom in a direction opposite to valve closing movement of said stem, together with means for oscillating said lever, comprising a float and an arm projecting beyond said stem in the path of float movement.

3. The combination with a ported tube provided with a self closing valve, of a part connected with said valve and provided with an annular groove of arcuate profile, pawl levers fulcrumed at opposite sides of said part and engageable in said groove for the support of said valve, laterally offset arms projecting past said part and a float engageable with said arms and adapted to trip said pawl levers for the release of said valve, the portions of said levers engaged in said groove being slightly longer than the radial distance from their respective fulcrums to said groove whereby to wedge under the weight of said part and said valve, the releasing movement of said lever portions being opposite in direction to the closing movement of said valve and part and the profile of said groove being adapted to facilitate the releasing movement of said lever portions.

4. A filling nozzle adapted to be introduced through elongated filler openings and provided with self closing valve mechanism, said nozzle comprising a tube of sufficient length to extend through the filling opening and provided with a port therebeneath, a sleeve valve slidable along said tube between an upper open position and a lower closed position in registry with said port, a dog pivoted for movement from a valve supporting position in a direction opposite to the closing movement of said valve to a valve releasing

position, said dog in its first mentioned position being adapted to wedge under the weight of said valve, a means connected with said valve and co-operating with said dog for the support of said dog and of said valve in its open position, said means having a configuration substantially concentric with the pivot of the dog whereby to be adapted to facilitate the release of said dog from its wedged position, and means for operating said dog.

5. A nozzle adapted for rapid delivery of liquids through elongated filler openings, said nozzle comprising an elongated tube provided with a discharge port adjacent its delivery end, a sleeve valve movable for the control of discharge through said port and associated with said tube adjacent said port, said sleeve valve being adapted to let liquid flow through said tube and port substantially unimpeded when open, and being positioned to operate immediately adjacent the point of discharge when closed, whereby to prevent material liquid delivery following the closing of said 20 valve, a float operated trip detent mechanism operatively arranged to hold said valve in an open position subject to release by said float, said valve being automatically closable upon release.

6. In a device of the character described the combination with a tube provided with a discharge port opening laterally through its side, and a float guide portion beyond said port, a closure for said tube between said discharge port and guide portion, a valve stem 25 slideable through said closure, a sleeve valve connected with said stem and arranged to control delivery through said port, a trip means including a float and a float operated detent for said stem arranged within said guide portion below said closure.

7. In a device of the character described the combination with a delivery tube having a laterally opening discharge port and a float 30 guide portion therebeyond, of a closure for said tube between said port and said guide portion, a sleeve valve operatively associated with said tube for the control of delivery through said port, said valve being gravity operated to its closed position, a control part connected with said valve for movement therewith, a wedging means pivoted for engagement to restrict the movement of said part and valve in a valve closing direction and a float operatively arranged to effect the release of said means for said part whereby to permit the gravity closing of said valve.

8. In a device of the character described, the combination with a delivery tube and a 35 valve controlling delivery therethrough, of a part connected with the valve, pivotally mounted wedge members disposed at opposite sides of said part and in motion receiving engagement therewith the pivots of said members being spaced from said part at a dis-

tance less than the effective radii of said members and in advance of the point of engagement of the respective members with said part whereby said members are adapted to act thereon with increasing wedging pressures in the closing direction of movement of said valve and part, said pressures being balanced upon said part by reason of the disposition of said members at opposite sides thereof, a float operated means for moving said members in wedge releasing directions opposite to the closing direction of movement of said part whereby to free said part and valve for closing.

9. In a device of the character described, the combination with a delivery tube and a valve controlling delivery therethrough, of a part connected with the valve, pivotally mounted wedge members disposed at opposite sides of said part and in motion receiving engagement therewith the pivots of said members being spaced from said part at a distance less than the effective radii of said members and in advance of the point of engagement of the respective members with said part whereby said members are adapted to act thereon with increasing wedging pressures in the closing direction of movement of said valve and part, said pressures being balanced upon said part by reason of the disposition of said members at opposite sides thereof, a float operated means for moving said members in wedge releasing directions opposite to the closing direction of movement of said part whereby to free said part and valve for closing, said means including lever arms projecting from each such member transversely beyond said part.

10. A valve controlling trip mechanism comprising the combination with a valve and stem, of dogs pivoted at opposite sides of said stem and arranged for engagement therewith, each of said dogs including a laterally off-set lever projecting beyond said stem to a position beneath the fulcrum of the other dog and a float arranged to act on the projecting ends of said lever arms for the pivotal adjustment of said dogs in opposition to the tendency of movement of said stem, said stem having a configuration adapted to permit said dogs to releasably engage it with opposed wedging pressures and said dogs being pivoted beyond the portion of the stem engaged thereby and at a distance from the stem less than their effective radii whereby to be wedged upon the stem in a valve closing movement thereof unless disengaged therefrom by said float.
